UNITED STATES PATENT OFFICE.

PETER ZIMBELMANN, OF AURORA, ILLINOIS.

ROOF CONSTRUCTION.

1,318,125.

Specification of Letters Patent.

Patented Oct. 7, 1919.

Application filed March 27, 1919. Serial No. 285,566.

To all whom it may concern:

Be it known that I, PETER ZIMBELMANN, a citizen of the United States, and a resident of the city of Aurora, county of Kane, and 5 State of Illinois, have invented certain new and useful Improvements in Roof Constructions, of which the following is a specification.

My invention relates to improvements in 10 roof constructions and has for its object the provision of an improved construction of this character whereby a roof already built may be readily repaired.

Other objects will appear hereinafter.

15 The invention consists in the combinations and arrangements of parts hereinafter described and claimed.

The invention will be best understood by 20 reference to the accompanying drawings forming a part of this specification, and in which,

Figure 1, is a perspective view of a portion of a roof embodying the invention,

Fig. 2, a similar view, with portions 25 moved and broken away, and

Fig. 3, a perspective view of one of a plurality of repairing plates employed in the construction.

The preferred form of construction, as 30 illustrated in the drawings, comprises a sheet metal repairing plate 4 adapted to be placed over one roof shingle and slipped under the next shingle above, as indicated, said plate being provided at its lower edge with 35 an upwardly turned flange 5 adapted to embrace the corresponding lower edge of the corresponding shingle, as indicated. The flange 5 on each of the plates 4 is cut away at one end to form a notch 6 adapted to 40 receive the flange on an adjacent plate so as to permit of lateral overlapping of the plates in repairing a roof. Some of the repairing plates 4' are made of a length to extend completely under the exposed portion

45 of the upper shingle and part way under the next shingle above, as indicated, and whereby a leak or bad place in two adjacent portions of the roof may be sometimes repaired by the use of a single repairing plate, the 50 lower portion of the plate 4' serving to cover a leak in a lower shingle and the upper portion of said plate passing under a leak in an upper shingle, thus repairing

both. After the repairing plates are placed in position as indicated, suitable nails 7 are 55 driven through the shingle at the proper places to further secure them in place.

At the ridge of the roof, two sheet metal strips 8 are placed, one on each side of but adjacent to the ridge and each provided 60 with an outwardly and downwardly extending engaging flange or lip 9. A ridge plate 10 is also provided and is adapted to rest over the ridge of the roof as shown, being provided at its lower edges with inwardly and upwardly extending flanges 11 65 adapted to engage with the flanges or lips 9, as shown. By this arrangement, the ridge of a roof may be readily repaired or sealed against leakage by placing strips 8 on each 70 side thereof, as indicated, and by slipping sections of ridge plate 10 into place from the end or gable of the ridge, as will be readily understood.

While I have illustrated and described the 75 preferred form of construction for carrying my invention into effect, this is capable of variation and modification without departing from the spirit of the invention. I, therefore, do not wish to be limited to the 80 precise details of construction set forth, but desire to avail myself of such variations and modifications as come within the scope of the appended claims.

Having described my invention, what I 85 claim as new and desire to secure by Letters Patent is:—

1. A roof construction comprising a sheet metal plate adapted to be placed over one shingle and slipped under the next shingle 90 above, said plate being provided at its lower end with an upwardly bent flange adapted to embrace the lower edge of said one shingle, said flange being cut away at one end to form a notch to facilitate lateral overlapping of said plates, substantially as described.

2. A roof construction comprising a sheet metal plate adapted to be placed over one shingle and of a length to be slipped under 100 the whole exposed portion of the next shingle above and under the next shingle above that, said plate being provided at its lower end with an upwardly bent flange adapted to embrace the lower edge of said one shingle, said flange being cut away at one end to 105

form a notch to facilitate lateral overlapping of said plates, substantially as described.

3. A roof construction comprising a sheet metal plate adapted to be placed over a shingle and of a length greater than the exposed portions of two adjacent overlapped shingles, substantially as described.

In testimony whereof I have signed my name to this specification in the presence of 10 two subscribing witnesses.

PETER ZIMBELMANN.
